TIE ROD FOR CONCRETE FORMS

Samuel S. Colt, Orange, N. J.

Application November 28, 1934, Serial No. 755,142

2 Claims. (Cl. 25—131)

This invention has for its object to provide a novel method and means for mounting tie-rods in form wall assembling and holding relation, subject to loosening of such tie-rods for withdrawal from concrete cast in the form, whereby, upon dismantling of the form, such tie-rods may be quickly and easily withdrawn from the finished concrete, and thus salvaged, together with all associated form building and assembling material, for repeated use.

In the method of constructing, assembling and disassembling of concrete casting forms, of the type comprising opposed and spaced form walls secured in position by tie-rods extending therebetween and therethrough, as heretofore practiced, the outwardly projecting end portions of the tie-rods have been utilized to support external form retaining and locking devices. Owing to the nature of these devices, the tie-rods could in no way be loosened relative to the concrete cast in the form before dismantling said form, and consequently the tie-rods would be so set and bound in and to the concrete mass that it is often impossible to withdraw the same from the concrete after the form was taken down. In such case, the ends of the tie-rods would have to be broken or severed at the surface of the concrete, thus preventing salvage of the tie-rods. Another difficulty experienced under the old practices, was that the projecting ends of the tie-rods would be so bent and distorted that withdrawal of the same from the finished walls would be so obstructed as to very greatly increase the labor of extraction, if not altogether preventing such extraction. Attempts to overcome these difficulties have resulted in a practice involving the provision of sectional tie-rods, i. e. tie-rods having exteriorly projecting end pieces which were detachably coupled to an intermediate tie-rod section disposed wholly within the form interior, whereby, on dismantling the form, such end pieces could be removed, leaving the main section of the tie-rod imbedded in the finished concrete wall, and therefore incapable of recovery for reuse. This latter practice, of course, is expensive, and involves a very considerable waste of material in the form of such non-recoverable tie-rod sections.

Having the difficulties and disadvantages of the above-mentioned practices in mind, my present invention was conceived with a view of overcoming the same by providing a novel method and means for so mounting and manipulating the tie-rods, that the same can be rotated about their longitudinal axes while the concrete cast in

the form is still somewhat green, i. e. not finally set and hardened, and while the form is still retained in operative assembled supporting relation to the concrete cast therein. Such turning of the tie-rods under such conditions operates to loosen the same from the concrete mass, thus freeing the same from adhesion thereto, whereby, when the concrete has ultimately cured to final hardened condition, resistance to longitudinal withdrawal of the tie-rods therefrom is substantially avoided, so that extraction thereof is wholly practicable, with the result that tie-rods are easily recovered or salvaged so as to be again available for further use. Not only is this so, but, furthermore, by the novel method and means involved in my present invention, single piece tie-rods may be utilized, thus eliminating the cost of coupling devices and like parts necessary to sectional types of tie-rods and consequently effecting further economy; and finally by the novel method and means comprising my present invention, the labor of erecting and dismantling forms is considerably decreased, and these operations can be effected much more rapidly and economically.

In the accompanying drawing, means are shown whereby one-piece tie-rods may be mounted and manipulated subject to salvage from the cast concrete after dismantling the form structure of which they are a part, all pursuant to a novel method of procedure in accordance with this invention.

In said drawing; Fig. 1 shows a fragmentary transverse vertical section of a concrete casting form structure utilizing one-piece tie-rods equipped with form wall retaining means so as to be subject to manipulation in accordance with this invention, the retaining means being shown in side elevation; Fig. 2 is a similar view with the retaining means shown in section; Fig. 3 is an end view, viewed from left to right in Fig. 1. Fig. 4 is a side elevation, Fig. 5 an end elevation and Fig. 6 a top plan view of a modified form of retaining means adapted to the manipulation of the tie-rod in accordance with this invention. Fig. 7 is a side elevation of a modified form of retaining means including a locking wedge in permanent coupled relation thereto.

Similar characters of reference are employed in the above described views, to indicate corresponding parts.

Referring to the drawing, the reference characters 10 and 11 respectively indicate laterally opposed walls of a form, each being respectively provided on their exterior sides with vertical bat-

tens 12 and 12' over which are arranged pairs of horizontally extending waler 13 and 13'.

Extending between the waler 13 and through the form wall 10, thence across the form interior 5 to and through the form wall 11, to project outwardly between the waler 13' associated with the latter wall, is a continuous or one-piece tie-rod 14.

Mounted on the end portion 14' of said tie-rod 10 14, which projects exteriorly from the form wall 10, is a novel retaining means comprising an abutment plate 15, which may be of any suitable 15 peripheral shape, but which is shown here as of rectangular form. This abutment plate 15 is applied in bridging relation to the waler 13 and over the exterior faces thereof. The abutment plate 15 is provided on its front face with a centrally disposed boss or hub 16, having therein an axially disposed substantially semi-spherical 20 countersunk socket or seat 17, from the bottom of which extends through the back of the abutment plate an opening 18, whereby the projecting end portion of the tie-rod 14 may be extended outwardly through said opening 18 and 25 socket or seat 17. Nail openings 19 are provided at suitable locations in the body of the abutment plate 15, whereby fastening nails 20 may be driven therethrough and into the waler 13, to thereby retain the abutment plate in fixed 30 assembled relation to the latter. The abutment plate may be suitably reenforced and stiffened by reenforcing ribs 21 extending from the boss or hub 16 over and integral with the outlying areas of the plate body. Cooperative with said abutment plate 15 is a combined tie-rod manipulating 35 and form wall retaining means, the same comprising an elongated body 22 having an axial bore 23 extending therethrough from end to end thereof, through which the exteriorly projecting 40 end of the tie-rod 14 may pass. Formed at the inner end of said body 22, as an integral part thereof, is a substantially semi-spherical bearing element 24 which fits into an is embraced by the socket or seat 17 of said abutment plate 15 so 45 as to be capable of both rotation therein as well as angular adjustment thereto. Preferably the bearing face of this bearing element 24 is provided with one or more annular concentric channels 25, which reduce the area of the contacting 50 surfaces of said bearing face with those of the socket or seat 17 whereby friction consequent upon movement of the one relative to the other is minimized. Said bearing element 24 is of greater diameter than the diameter of the body 22, thus 55 forming at the juncture of these parts an annular shoulder 26. It is preferable to couple the abutment plate 15 and body 22 against separation one from the other but nevertheless in such manner that the latter is free for rotary and 60 angular movement relative to the former. This is accomplished by providing, integral with the periphery of the end portion of the boss or hub 16, a plurality of circumferentially spaced coupling lugs or tongues 27, the free end portions 65 of which are bent inwardly around the shoulder 26 and thus into embracing relation to the bearing element 24 of said body 22. Intermediate its ends, said body 22 is provided with laterally projecting internally threaded necks 28 which 70 respectively extend from opposite sides thereof in aligned relation one to the other. Engaged through said necks are manipulatable set screws 29 which are opposed one to the other so as to enter opposite sides of the bore 24 of the body 75 22. The outer end portion of the body 22 is

shaped to provide a polygonal head 30 to furnish wrench or like tool engageable faces, whereby a wrench or like tool may be applied thereto for turning the same and thus impart turning or twisting motion to a tie-rod 14 to which the body 5 22 is secured. The body 22 is strongly affixed to one end of the tie-rod 14, which extends there-through, by tightening home the opposed set screws 29, which also serve to center the tie-rod so that the same and the body 20 are substantially concentric.

Mounted on the opposite end portion 14'' of the tie-rod 14, which projects exteriorly from the opposite form wall 11, is a retaining means of the same form and construction as has been 15 above described, the detail parts of which are identified in the drawing by corresponding reference letters. In applying such retaining means to the tie-rod end portion 14'', the abutment plate 15 is disposed parallel to the waler 13', so 20 that its ends abut wedge members 31, which are interposed between these parts, whereupon the body 22 is strongly affixed to the tie-rod end portion 14'' by tightening home the opposed set screws thereof.

To lock the form up tightly so as to hold the assembled elements thereof from yielding or displacement when concrete is cast into the form interior, the wedge members 31 are driven tightly down, thus drawing into close interfitting relation the described form tying and bracing structure, it being understood that suitable spreader means (not shown) are usually employed to brace the form walls 10 and 11 against inward displacement or collapse. It will be noted that 35 the abutment plate 15, as canted by the wedges, will angularly adjust itself to the body 22 which retains the alignment to the longitudinal axis of the tie-rod 14, and consequently no bending or 40 distorting strains or stresses are imparted to the tie-rod, which remains straight and true throughout its length. After the form has been 45 thus set up, it will be obvious that all relative movement of the form parts and retaining devices in the direction of the longitudinal axis of the tie-rod is prevented, while nevertheless the bodies 22 of the opposite retaining means, and the tie-rod to which they are affixed, are subject to rotation relative to the abutment plates 15 and form wall structures abutted by the latter.

When the form is assembled, as above described, the concrete is poured thereinto. After the poured concrete has set to somewhat solidified condition, but before it has finally aged to ultimate dry hardened condition, in other words, while it is still somewhat green, the tie-rods 14 are rotated or twisted. This is done by application of a wrench to the polygonal head 30 of either one or the other of the bodies 22 of the retaining means with which the exteriorly projecting end portions thereof are provided; whereupon, by means of leverage exerted upon manipulation of the wrench, the body 22 may be turned or twisted back and forth, thus turning or oscillating the tie-rod 14 about its longitudinal axis throughout 65 its length. The body 22 affixed to the end of the tie-rod opposite to that to which the turning force is thus applied, is free to turn with the tie-rod and relative to the abutment plate with which such body is associated. Owing to the provision 70 of the semi-spherical bearing elements 24 as rotatably supported by the sockets or seats of the abutment plates 15, the rotary movements are maintained concentric to the axis of the tie-rod, and consequently no bending or distortion of the 75

latter occurs. This turning of the tie-rod 14 is accomplished without in any way relaxing the form structure or dismantling or removing any part thereof, and therefore is performed while 5 the form remains in initial supporting and holding relation to the concrete cast therein, and consequently no risk of injury or damage to the concrete casting occurs. The turning of the tie-rod under the specified conditions, thoroughly loosens 10 the same in the body of the cast concrete mass, and eliminates any adhesion of the concrete material to those surfaces of the tie-rod in contact therewith. The tie-rods having been loosened in the manner described, the form is retained in operative 15 assembled relation to the concrete cast therein until the latter dries out and hardens to a condition in which the same is self-sustaining, whereupon the form is dismantled.

To dismantle the form, the bodies 22 of the 20 retaining means are disengaged from operative affixed relation to the tie-rod end portions by relaxing the set-screws 29, and by removing the 25 nails 20 the abutment plates 15 are released from affixed relation to the form wall walers, whereupon 30 the retaining means may be slid outwardly off of the tie-rod end portions. The retaining means being thus removed, the form wall structures may thereupon be stripped from the sides of the concrete casting, leaving the tie-rods 14 exposed for extraction, or the tie-rods may be 35 withdrawn before stripping away the form wall structures. Owing to the fact that the tie-rods have been thoroughly loosened from any adhesion to the concrete mass, by the turning or twisting operations above described, the same may be 40 easily pulled longitudinally outward from the concrete and thus withdrawn therefrom without risk of distortion or breakage, and consequently when so withdrawn, the same are salvaged in good 45 condition subject to reuse in further or other form building operations. In many cases the tie-rods may be thus extracted by hand, but there are many known forms of tie-rod extracting tools which may be utilized, if desired, in aid of such tie-rod extracting operations.

In Figs. 4 to 6 inclusive, I have shown a modified construction of retaining means which can be used in accordance with the principles of this invention, the modification consisting in eliminating 50 the set screw arrangement for affixing the means to a tie-rod end portion, and in making the outer end portion of the body 22 in separable clamp sections, comprising one clamp-section 32 integral with the body 22 and the other clamp-section 55 33 separably opposed to said first mentioned clamp-section. The respective clamp sections are provided with oppositely and laterally projected perforate ears or lugs 34 and 35 which are opposed, when the clamp-sections are assembled 60 about the tie-rod end portion, so that bolts 36 may be engaged therethrough to draw the clamp sections together into biting and holding relation to

the tie-rod end portion. If desired, a set screw 37 may also be provided for setting the retaining means in desired location on the tie-rod pending final tightening up of the clamp-sections. In other features of construction, the modified form of retaining means is the same as already described in connection with the first mentioned form thereof, as will be understood by reason of the application thereto of corresponding reference characters.

In Fig. 7 I have shown a further modified form of the retaining means as adapted for coupled association with a wedge device 38. The modification in this case resides in the abutment plate, which is eliminated and in place thereof a 15 socketed element 39, adapted to receive the bearing element 24 of the body 22, is movably coupled to the wedge device 38, to slide upon the outer face of the latter, by means of coupling lugs 40, which are in-turned around marginal flanges 41 with 20 which the outer face portion of the wedge device 38 is provided.

Having now described my invention, I claim:

1. A concrete casting form comprising opposed form wall structures, a round tie-rod in one continuous piece extending through the form with its end portions respectively projecting outwardly from said form wall structures, form retaining means on the respective exteriorly projecting end portions of said tie-rod, said retaining means each comprising a portion stationary in relation to the adjacent form wall structure and a body portion rotatable in relation to said stationary portion, cooperative ball and socket bearing means between said rotatable and stationary portions, said rotatable portions having wrench receiving means, means for affixing the rotatable portions to said tie-rod end portions and substantially concentric to the longitudinal axis of the tie-rod, whereby, while the form is locked up in supporting relation to the concrete mass cast therein and before said mass sets to hardened dry condition, rotative force applied to a rotatable portion is transmitted to said tie-rod to turn the same relative to the cast concrete without accompanying longitudinal movement to thereby loosen the same for easy withdrawal from the latter upon dismantling the form.

2. A concrete casting form as defined in claim 1 wherein locking wedge means is interposed between the stationary portion of a retaining means at one end of the tie-rod and the adjacent form wall structure, said stationary portion being adapted, by functioning of the ball and socket bearing means, to adjust itself angularly to the associated rotatable portion without disturbing the alignment of the latter to and upon the tie-rod or bending the latter, and means for coupling the wedge means in non-separable relation to said stationary portion yet free to move relative thereto.

SAMUEL S. COLT.
